VAPOR-ELECTRIC DEVICE

William E. Pakala, Pittsburgh, Pa., assignor to
Westinghouse Electric Corporation, East Pitts-
burgh, Pa., a corporation of Pennsylvania.

Application March 8, 1947, Serial No. 733,394

11 Claims. (Cl. 250—27.5)

1 My invention relates to vapor-electric devices, and, particularly, to means for maintaining a high state of evacuation in sealed off devices.

In the operation of vapor-electric devices, it is frequently desirable to operate vapor-electric valves without the necessity of maintaining constant evacuation devices for maintaining an operative pressure in the valves.

Also it is frequently found desirable to provide anode shields or anode arms extending outside the main portion of the container so that a minimum of shielding is required about the anodes. However, in the operation of vapor-electric devices, there has been found a strong tendency for the vapor stream arising from the cathode to impel non-condensing gases into the anode shields so that a relatively high gas pressure may accumulate in the vicinity of the anodes and thus result in arc backs or other faulty operation.

Also in the operation of sealed off vapor-electric devices, gas pressure is built up either because of infinitesimal leakages through the walls of the containers or by liberation of occluded gases in the various portions of the converter itself.

Heretofore, it has been found necessary to frequently return the sealed off valves to a processing center where they are degassed and prepared for further operation.

In a construction according to my invention, I have arranged means for relieving gas pressure in the anode shields adjacent to the anode structures and have also provided means for compressing any residual gas or gases, otherwise found in the container, into a relatively small compartment so that the valve may operate over long periods of time without necessity of re-pumping or re-fitting for operation.

To relieve the pressure in the anode shields, I have provided a gas passage from a point adjacent the top of the shield to a point in the container remote from the cathode blast.

I also prefer to provide a jet nozzle intermediate the ends of the container so that the vapor blast carries the non-condensable gases into a portion of the container remote from the operating electrodes. At least that portion of the container remote from the electrodes is provided with a cooled surface for condensing the cathode vapor, and suitable means is utilized by which the condensed cathode vapors while returning to the cathode impel any gases in their vicinity into the closed receptacle where they are effectively sealed off and prevented from deleteriously affecting the operation of the device.

2 Accordingly, an object of my invention is to provide a sealed vapor-electric device having a long useful life.

A further object of my invention is to provide means for relieving the gas pressure in anode shields.

A further object of my invention is to provide means for segregating the gases out of the main portion of the container of a vapor-electric device.

It is a still further object of my invention to provide means operative by the condensed cathode vapor for impelling non-condensable gases into a trapped container.

15 Other objects and advantages of my invention will be apparent from the following detailed description, taken in conjunction with the accompanying drawing, in which:

Figure 1 is a sectional elevation of a vapor-electric device embodying my invention;

Fig. 2 is a fractional sectional elevation showing the details of the gas impelling devices; and

Fig. 3 is a sectional view, taken along the line III—III, showing the bottom arrangements in a container according to my invention.

In the exemplary embodiment of my invention, a metallic container 1 is provided, preferably in substantially cylindrical form, and has a pool-type cathode 2 composed of suitable vaporizable re-constructing material, such as mercury, mercury amalgam, or gallium in the bottom of the container.

One or more anode shields 3 are provided, preferably in the form of substantially tubular arms extending outwardly from the container 1 at a point adjacent, or in proximity to, the cathode surface, the anode or anodes 4 being supported in suitable insulating bushings 5 at a point adjacent the outer extremities of the anode shields 3. The vapor blast arising from the surface of the cathode tends to compress non-condensable gases into the anode shields 3, and I have provided substantially tubular passages 6 from the outer extremities of the anode shields

40 3 to a portion of the container 1 substantially remote from the cathode 2 so that any pressure in the anode shields 3 will be relieved by passage of gas into the container 1 at a point remote from the cathode 2. Preferably, the relieving passage 6 is constructed so that it slopes from the anode shields 3 to the vicinity of the container 1 so that any cathode vapor condensed or otherwise making its way into the relieving passage 6 will be returned directly to the container

45 55 1 instead of being propelled into the vicinity of

the anodes 4 where it might produce faulty operating conditions.

My improved construction is not only applicable to the smaller tubes which are usually operated sealed off but may be applied to the largest power devices of one or a plurality of anodes.

Where a plurality of anodes are utilized in a single container, it is desirable to insulate the cathode dish 7 from the container 1, and where continuous excitation rather than intermittent excitation is utilized such insulation is a practical necessity. Where intermittent operation of the ignitron type is utilized, the insulation may, of course, be omitted if desired.

In any event, I prefer to provide a plurality of ignitor electrodes 8 and one or more holding or relieving electrodes 9 preferably mounted through the bottom of the container 1 by insulators 10.

It is frequently possible or desirable to place two alternately conducting anodes 4 in the same container 1, for this purpose, I have shown two anodes 4 as associated with a single cathode 2. There is an ignitor electrode 8 and a cathode spot-holding electrode 9 or relieving electrode for each of the main anodes 4 so that regardless of the previous history of the device, a cathode spot will be initiated and maintained long enough for the initiation of a main arc to the respective anodes 4.

In order to clear out any vapors or non-condensable gases which might leak into or be produced within the container 1, I have provided a compartment 15 having a liquid seal 16 into which the gases are impelled by means to be presently described. While this compartment 15 may be in any one of several forms, I prefer to provide a relatively L-shaped flange 17, the outer edge 18 of which is secured in gas-tight relation to the sides of the container 1 at a point somewhat above the bottom thereof and which then extends in spaced relation thereto to a point adjacent the bottom and provide sufficient mercury in the bottom of the container 1 so that the bottom of the flange 17 is dipping into mercury to provide a liquid seal 16. If only one anode 4 is used, the bottom of the container may be relatively flat so that the cathode pool 2 and the mercury seal 16 are continuous. However, if a plurality of anodes 4 are used, it is desirable to insulate the cathode pool 2 from the container 1 proper and, for this reason, I have shown the bottom as being reentrant to provide a relatively narrow trough or groove 19 extending upwardly along the depending flange 17 and having a depressed central portion to which the cathode dish 7 is attached by means of a suitable insulating bushing 20.

The various excitation electrodes 8 and 9 are supported by and electrically connected through insulating bushings 10, preferably attached to the bottom of the container 1 and in the event of an insulated cathode, preferably outside the insulating member 20.

In order to condense or return the reconstructing cathode material, at least a portion of the container 1 is provided with cooled condensing surfaces, preferably by applied cooling coils 21 to the exterior of the container 1 so that the interior surface provides a condensing area.

It is well known that the cathode blast operates as a pumping medium to impel gases and vapors into the portion of the container 1 adjacent the condensing surfaces.

The condensed cathode material is collected in

a trough 24, preferably adjacent the bottom of the nozzle 25 or orifice and at least at a point above the sealed compartment 15. The condensed material is then returned to the cathode 2 by means of a fall tube 26 extending from the trough 24 in sealed relation to a point inside the sealed compartment 15. Preferably, the fall tube 26 extends relatively near to the bottom of the sealed compartment 16 so that the material sealing the compartment 15 also provides a vapor seal for the fall tube 26. By providing the fall tube 26 of a shape having an open portion 30 exposed to the gases accumulated in the space above the pumping jet 25 and having another opening 31 for receiving the condensed cathode material, a springle pump action is secured. The drops of condensed cathode material entering the open tube 26 at 31 and trapping portions of gas between the drops which are impelled by the weight of the condensed material through the fall tube 26 and into the cathode pool 2, or in the event a separate seal is provided, the displaced sealing material will flow into the depression 19 and return to the cathode pool 2.

For purposes of illustration, I have shown and described a specific embodiment of my invention, and it will be apparent that changes and modifications can be made therein without departing from the true spirit of my invention or the scope of the appended claims.

I claim as my invention:

1. A vapor-electric device comprising a sealed substantially evacuated container, the bottom of said container being reentrant to provide a channel adjacent the walls of the chamber, a flange secured to the wall of the chamber in gastight relation and extending into said channel, a quantity of mercury in said channel providing a sealed compartment under said flange, a mercury pool cathode covering at least a portion of said bottom, means for collecting mercury above said compartment and a fall tube extending from said mercury collecting means into said compartment.

2. A vapor-electric device comprising a closed container, a pool-type cathode of vaporizable reconstructing material, an anode shield opening in the vicinity of the cathode, an anode in said shield at a point remote from said cathode, a gas passage between said shield and a portion of the container remote from the cathode, and means for producing a flow of gas and vapor into a portion of the container remote from the cathode.

3. A vapor-electric device comprising a closed container, a pool-type cathode of vaporizable reconstructing material, an anode shield opening in the vicinity of the cathode, an anode in said shield at a point remote from said cathode, a gas passage between said shield at a point remote from the cathode and a portion of the container remote from the cathode, means including a condensing surface for producing a flow of gas and vapor into a portion of the container remote from the cathode, and a fall tube utilizing condensed vapor on its return to the cathode to impel non-condensing gases into a restricted portion of the container.

4. A vapor-electric device comprising a sealed chamber, a vaporizable reconstructing cathode in said chamber, an anode cooperating with said cathode, a shield enclosing said anode and open to said cathode, a passage for relieving gas pressure in said shield, a liquid sealed compartment in said chamber, means for condensing the vapor emanating from the cathode and a fall tube utilizing the condensed cathode material for impelling

gases from said chamber into said compartment.

5. A vapor-electric device comprising a substantially evacuated container, a quantity of mercury in the bottom of the container, a flange attached in gastight relation to the side of said container and extending in spaced relation thereto and into the mercury to provide a mercury sealed compartment, mercury collecting means above said compartment and a pump actuated by mercury collected in said mercury collecting means for impelling gas from said container into said compartment.

6. A vapor-electric device comprising a container, a pool of vaporizable cathode material at the lower portion of said container, an anode shield opening in the vicinity of the pool of cathode material, a passage between a portion of the anode shield remote from the pool of cathode material and a portion of the container remote from the cathode pool and a cooled surface for reducing the vapor pressure at the end of the container remote from the cathode pool.

7. A vapor-electric device comprising a container, a pool of vaporizable cathode material at the lower portion of said container, a cathode shield opening in the vicinity of the pool of cathode material, a passage between a portion of the anode shield remote from the pool of cathode material and a portion of the container remote from the cathode pool, a trapped space in said container, condensing means for reducing the vapor pressure at the end of the container remote from the cathode pool, and a fall tube for pumping non-condensing gases in said container into said trapped space.

8. A vapor-electric device comprising a sealed chamber, a vaporizable reconstructing cathode in said chamber, an anode shield extending externally of said chamber and opening in proximity to said cathode and a gas passage between said shield and said chamber.

9. A vapor-electric device comprising a sealed chamber, a vaporizable reconstructing cathode in

said chamber, an anode shield extending externally of said chamber and opening in proximity to said cathode, a gas passage between said shield and said chamber and a nozzle orifice intermediate the ends of said chamber.

10. A vapor-electric device comprising a sealed chamber, a vaporizable reconstructing cathode in said chamber, an anode shield extending externally of said chamber and opening in proximity to said cathode and a gas passage between said shield and said chamber, a nozzle orifice intermediate the ends of said chamber, a cooled surface for condensing vapors passing through said orifice, a liquid sealed compartment in said chamber and pumping means actuated by the condensate for impelling non-condensing gases from said chamber into said sealed compartment.

11. A vapor-electric device comprising a sealed substantially evacuated container, a mercury cathode in said container, an anode cooperating with said cathode, means for condensing mercury vapor, means for collecting the condensed mercury at a position above the cathode, a mercury sealed compartment, a fall tube between said mercury collecting means and said sealed compartment so that condensed mercury returns to the cathode through the fall tube and the mercury sealed compartment.
